UNITED STATES PATENT OFFICE.

CHARLES J. PILLIOD, OF TOLEDO, OHIO, ASSIGNOR TO DANIEL SEARLES, TRUSTEE, OF TOLEDO, OHIO.

ADAPTER MEANS FOR FURNACE DOORS.

Application filed January 10, 1921. Serial No. 436,087.

To all whom it may concern:

Be it known that I, CHARLES J. PILLIOD, a citizen of the United States, and a resident of Toledo, in the county of Lucas and State 5 of Ohio, have made an Invention Appertaining to Adapter Means for Furnace Doors; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to fire doors for locomotives, or the like, and particularly to an adapter ring for use in connection therewith.

20 The object of my invention is the provision in connection with a stoke hole of a locomotive, furnace, or the like, and a fire door therefor, of means for adapting the fire door for use in connection with stoke holes of different shapes and styles, and 25 which also serves as a protecting means for the wall of a stoke hole and particularly for that part thereof with which the shovel of a stoker is likely to engage when fuel is being shoveled into the furnace.

30 A further object of the invention is the provision of an adapter or contour ring of the class described, which, when it becomes worn or broken, may be easily and quickly replaced without necessitating the replacement 35 of the entire door frame, as is now commonly the case.

The invention is fully described in the following specification, and while, in its broader aspect, it is capable of embodiment 40 in numerous forms, a preferred embodiment thereof is illustrated in the accompanying drawings, in which,

45 Figure 1 is a front elevation of a door frame and adapter ring embodying the invention in assembled form and with the doors open and parts broken away. Fig. 2 is a central vertical section of my invention applied to a locomotive with the associated doors closed. Fig. 3 is a front face 50 view of an adapter ring embodying the invention. Fig. 4 is an enlarged section thereof on the line 4—4 in Fig. 3 together with a fragmentary section of a casing wall. Fig. 5 is an enlarged section on the line 55 5—5 in Fig. 3, and Figs. 6 and 7 are en-

larged sections, respectively, on the lines 6—6 and 7—7 in Fig. 3, together with associated portions of a casing, with the latter in fragmentary section.

Referring to the drawings, 1 designates 60 the casing of a locomotive, or other, furnace having the customary stoke hole 2 therein, 3 a door frame mounted at the outer side of the opening and adapted to cooperate with one or more doors 4 to close the stoke 65 hole, as well understood in the art. The frame 3, in the present instance, forms a guide for a pair of oppositely sliding doors 4—4, which are operated by any suitable mechanism. The frame is secured to the 70 furnace casing by bolts 5, or in any other suitable manner, and has an opening 6 therein in register with the stoke hole 2 and substantially, but not necessarily, of the same size and shape as the stoke hole. 75

The frame 3 is outwardly spaced, particularly at its inner marginal edge portion from the casing 1, and an adapter ring 7 is disposed within the space and clamped by the frame to the casing 1 at the marginal edge of the opening 2. The adapter ring 7 is held rigidly centered or positioned within the frame 3 by a series of lugs 8, which project inwardly from the inner side of the frame 3 in outwardly spaced relation to 80 the opening 6 therein and in position to contact with the outer peripheral side of the adapter ring at spaced distances therearound, as shown. 85

The adapter ring 7 is of U-form in cross-section to form the loop or cross-portion 9 and the inner and outer spaced legs or flanges 10 and 11, with respect to the center of the ring, projecting inwardly therefrom. The loop portion 9 forms the outer face of 90 the ring and is adapted to bear flatwise against the inner side of the frame 3, at the inner marginal edge of the opening 6 therein, and is of a shape and size adapted to conform substantially to the shape and size of the opening 6. The outer leg or flange 11 of the ring preferably projects inwardly from the looped portion 9 at substantially a right angle thereto to bear at its free end against the casing 1 at the marginal edge of its opening, substantially as illustrated. This leg of the ring is drawn rigidly to the casing by the inward clamping action of the frame 3. In the present instance the leg 11 is shown as provided at 100 105 110

opposite sides of the frame opening, or at the ends of the ring, with outwardly turned feet or flanges 12 to facilitate contact of the ring with the casing at such points. The 5 outer leg 11 of the ring remains substantially constant in form for different sizes and shapes of stoke holes within a predetermined range but may, of course, be varied in form, if desired, to suit a particular shape 10 or style of stoke hole.

The inner leg or flange 10 of the ring is the one which is varied in form to suit stoke holes of different sizes and shapes, and in the present instance, is shown as having its 15 upper portion extending inward and downward on an incline. The lower portion of the flange 10 is broadened both inward and outward to form a tool guard 13, which, at its inner end, overlaps the outer edge wall 20 of the stoke hole 2 and at its outer end overlaps the lower edge wall of the frame opening 6. This guard protects both the frame and the casing from contact with the stoker's shovel, thereby insuring a considerable 25 prolongation of the life of both. So much trouble has been occasioned by reason of the stoker's shovels and other tool striking and causing injury to the lower edge wall of the stoke hole 2 of furnaces that one 30 of the rules for stokers on locomotives is that the shovel and other tools must not be permitted to strike the wall of the furnace opening. It is evident that the form of the inner flange or leg 10 of the ring may be 35 varied to suit the shape or size of the stoke hole 2 to which applied, and that the ring when worn or broken may be easily and quickly replaced without necessitating a replacement of the door frame.

40 I wish it understood that my invention is not limited to any specific construction, arrangement, or form of the parts, as it is capable of numerous modifications and changes, without departing from the spirit 45 of the claims.

Having thus described my invention, what I claim as new and desire to secure by Letters Patent, is,—

1. In combination, a furnace casing having 50 a stoke hole therein, a door frame clamped to the casing in surrounding relation to the hole, an adapter ring disposed within the inner marginal edge of the frame and clamped thereby to the marginal wall 55 of the stoke hole, said ring having an outer

flange with respect to the ring center which bears against the casing in surrounding relation to its stoke hole and having an inner flange shaped to adapt the frame opening substantially to the shape and size of the 60 casing hole and also forming a tool guard at its lower portion which laps the lower edge walls of both the frame opening and stoke hole.

2. In combination, a furnace casing having 65 a stoke hole therein, a door frame removably clamped to the casing in surrounding relation to the stoke hole, and an adapter ring removably disposed between the frame and casing, said ring being substantially 70 U-shape in cross-section with its flanges extending away from the door frame and the outer flange bearing at its free edge against the marginal wall of the stoke hole and with the inner flange free from engagement 75 with such marginal wall.

3. In combination, a furnace casing having 80 a stoke hole therein, a door frame removably clamped to the casing in surrounding relation to a stoke hole, and an adapter ring of substantially U-form in cross-section 85 with the flanges thereof projecting away from the door frame, the outer flange with respect to the ring center bearing inward against the furnace casing in surrounding relation to the stoke hole and the inner flange with respect to the ring center having inwardly flared upper and lower portions.

4. In combination, a furnace casing having 90 a stoke hole therein, a door frame removably clamped to the casing in surrounding relation to its stoke hole, an adapter ring disposed between the frame and casing and conforming in shape to and fitting 95 against the inner marginal edge of the frame opening and having inwardly projecting inner and outer flanges, with the outer flange with respect to the ring center bearing inward against the marginal edge 100 wall of the stoke hole and with the inner flange with respect to the ring center having its upper and lower portions inwardly flared, the door frame having portions 105 coacting with the ring to hold it in centered relation to the frame.

In testimony whereof I have hereunto subscribed my name to this specification.

CHARLES J. PILLIOD.
